SHIGEZO YUYAMA, OF BROOKLYN, NEW YORK.

INCANDESCENT ELECTRIC LAMP.

1,215,894.

Specification of Letters Patent. Patented Feb. 13, 1917.

Application filed April 19, 1916. Serial No. 92,079.

To all whom it may concern:

Be it known that I, SHIGEZO YUYAMA, a subject of the Emperor of Japan, and resident of Brooklyn, in the county of Kings and State of New York, have invented certain new and useful Improvements in Incandescent Electric Lamps, of which the following is a specification.

This invention relates to electric lamps and filaments and especially to incandescent light glowers so arranged that the greatest length or area of the same shall be located in a substantially horizontal position, the object of the invention being to afford direct downward action for the light rays of the lamp, as will be more fully described in the following specification, set forth in the claims and illustrated in the accompanying drawings, and wherein:

20 Figure 1 is a side elevation of an incandescent electric lamp looking at the film frame from one corner.

25 Fig. 2 is an enlarged view of the filament and its frame from the front.

Fig. 3 is a side view of the same.

Fig. 4 is a view from below.

In the construction and arrangement of incandescent glow lamps it has heretofore been the practice to suspend the filament vertically so that the light therefrom is radiated laterally throughout the length of the filament and its loops and coils. When the filament is strung on frames the same plan has been pursued and substantially the entire filament is arranged in vertical windings or loops and the tendency of these constructions is to cause lateral illumination.

40 The purpose of the incandescent film lamp in a large majority of cases, however, is to secure downward illumination and unless reflectors are used, the use of the vertical filament results in a great loss of efficiency in the average lamp, and in many cases reflectors are used to divert horizontal rays from the vertical filaments to vertical rays for use.

45 This indirect illumination, as above described, results in considerable loss of the lighting efficiency of the lamp.

50 The improved construction of the present invention, while designed to afford a maximum lighting power at the bottom of the glower and in a horizontal position, at the same time provides an abundance of light means on other lines which may be arranged to so conform with the interior of the re-

flector as to be also concentrated indirectly with the direct rays beneath the lamp.

Attempts have been made to arrange glowers horizontally but they have been supported at one end only and the fragile nature of the filament causes it to break and disintegrate after a brief period. When the filament is supported from both ends its life is prolonged because the leverage of a free end is eliminated. In the present invention the supports at each end of the horizontal parts of the filament are resilient and enables it to withstand shocks and blows while the usual rigid supports render the filament liable to destruction on account of its brittleness.

55 The bulb 10 forming a part of this lamp may be of the substantially pear shaped variety but somewhat larger at its lower end and where its outline is an arc of somewhat longer radius than the ordinary lamp and is perfectly convex and without irregularity or projection. At its upper end is the plug 11 to secure the lamp in a socket and the leading-in wires are inclosed in the usual glass stem 12. The said stem is flattened as at 13 a short distance below the exit point of the terminals and from this part a reduced stem 14 projects downward. Through the flattened part 13 extends a cross bar 15 having loops 16 on each side of the stem and the lower end of the stem 14 carries a cross bar 17, at right angles to the bar 15, and said bar 17 has lateral extensions 18 at each end parallel with the bar 15 and also having loops 19.

60 The ends of the terminals 20 turn downward and each projection has secured to it an end of the filament 22 as will be seen. The bar 15 is much shorter than the bars 18 as shown in Fig. 2 and the terminal extensions 21 are less in width than the said bars 18, and in Fig. 4 it will be seen that the distance apart and the expansion of the latter bars is practically equal and lines drawn from their corners will form a square. Over this square are strung the horizontal sections of the filament, one end of the same running from its terminal through an end loop 19 of the bar 18 and after taking a horizontal course is carried across the bar 15 forming one of the side sections 24 and being carried downward on the other side to the opposite bar 18. This winding is repeated and the other end of the filament is secured to the remaining terminal, thus forming a triangu-

- lar or wedge shaped structure, each side having a much less area than the lower side and consequently a larger volume of light will be generated at that side of the lamp. The space inclosed by the entire film may be regarded as a volume of light of that size and as this constitutes considerable space within the bulb, the light from such an arrangement would be considerable.
- 10 The most important result accomplished by this arrangement is the large light surface secured from the lower side of the lamp and at a point from which the greatest amount of light is desired. The lamp may 15 also be provided with a reflector having sides at the proper angle to divert the rays from the inclined sides 24 to vertical lines beneath the lamp.
- The arrangement of the carrying frame, 20 comprising the bars 15 and 18, and the stringing of the filament around the same provides a very substantial construction and braces the filament against dangers of destruction.
- 25 The filament may be made of any desired material which is capable of being strung about the frame and by actual demonstration it is found that a filament constructed and arranged as above described may be made 30 of practically the same length of material as lamps which are in common use but require no more power to heat nor cost no more to operate than the same ordinarily used lamps, and obviously this improved lamp gives better results on account of the disposal and arrangement of the source of light.
- It is obvious that the modified or otherwise arrangement of the parts may be resorted to without departing from the essential 40 features above described or from the scope of the appended claims.

What I claim as new is:

1. In an electric lamp, the combination with a transparent bulb, of a frame carried 45 by a vertical stem and comprising two lower and upper cross arms, and a filament strung around the frame in a wedge shape and the

lower members passing from one cross arm to the other and arranged parallel and horizontal.

50

2. In an electric lamp, the combination with a bulb, of an insulated frame comprising lower and upper cross arms, leading-in wires connected with the upper arm, and a filament of a single piece with its ends connected with the upper cross arm and strung around the arms in wedge-shape lines; the lower members being strung horizontally between the lower arms.

55

3. In an electric lamp, the combination with a bulb having an enlarged lower end, of an insulated frame carrying the leading-in wires, a bar at the lower end of the frame and having lateral extensions, a cross bar above and parallel with the extensions, and a glower filament strung from the extensions and over the cross bar.

60

4. In an electric lamp, the combination with a bulb having a lower enlarged convex end, of a stem carrying the leading-in wires, a bar at the lower end of the stem and having lateral extensions at each end, a cross bar through the stem above the first bar and parallel with the extensions, and a glower filament attached at its ends to the leading-in wires and wound about the extensions and the cross bar to form a wedge shaped outline with its greatest surface at the bottom.

70

5. In an electric lamp, the combination with a bulb, of an insulating stem carrying the leading-in wires, a cross bar in the stem and having loops, a second bar at the end of the stem, lateral extensions on the latter parallel with and longer than the cross bar, 85 and a glower filament strung around the cross bar and the extensions to form a wedge shaped frame whose base is the largest light giving side.

80

Signed at New York, in the county of New York and State of New York, this 27th day of March A. D. 1916.
